GEORGE WALTERS AND THOMAS SHAFFER, OF PHOENIXVILLE, PENN-SYLVANIA.

Letters Patent No. 68,267, dated August 27, 1867.

IMPROVED PILE FOR WROUGHT-IRON BEAMS OR GIRDERS.

The Schedule referred to in these Letters Patent and making part of the same.

TO ALL WHOM IT MAY CONCERN:

Be it known that we, GEORGE WALTERS and THOMAS SHAFFER, both of Phoenixville, Chester county, Pennsylvania, have invented certain improvements in Piles or Fagots for Wrought-Iron Beams or Girders; and we do hereby declare the following to be a full, clear, and exact description of the same.

Our invention consists of a pile or fagot, for wrought-iron beams or girders, composed of one or more bars for the web, and any appropriate number of bars for the flange or flanges, the said bars being arranged and permanently secured by bolts or rivets in the manner and for the purpose of effecting the advantageous results described hereafter.

In order to enable others skilled in the art to practise our invention, we will now proceed to describe the mode of carrying the same into effect, reference being had to the accompanying drawing, which forms a part of this specification, and in which—

Figure 1 is a transverse section of our improved pile or fagot for wrought-iron beams or girders.

Figure 2, a side view partly in section, and

Figures 3, 4, 5, 6, 7, and 8 illustrate our improvement as applied to fagots for forming bars of different transverse forms.

Similar letters refer to similar parts throughout the several views.

On reference to figs 1 and 2, *a a* represent two bars placed side by side, and cut to the desired length of the pile or fagot, these two bars forming the web, on each side and near the upper edges of which are arranged the bars *b, c, and d*, permanently secured together by bolts or rivets *e*. The middle bar *c* is made in sections or lengths arranged at such a distance apart from each other as to permit the passage between them of bolts or rivets *f*, which also pass through holes in the web, and serve to secure the latter permanently to the bars *b, c, and d*, which form the flanges. The pile, which approximates in shape to an H-beam, is now placed in a furnace and reduced to a welding heat, to be subsequently converted into a beam of the desired form and size by the action of the usual rolls.

A pile or fagot, constructed as above described, will retain its shape while it is in the furnace, and the bars being firmly bound together no cinder or other impurities can be lodged between them, and, being all plain, whatever impurities there may be in the iron are easily worked out.

The beam rolled from a pile or fagot composed of bars arranged and secured together as described, is more uniform, solid, and of better finish than beams rolled from ordinary fagots.

It will be understood that the web of the pile may be composed of a single bar, or of more than two bars; three bars or more than three bars, however, being necessary for each flange, so that one of the inside bars may be arranged in sections apart from each other to admit the transverse rivets or bolts *f*.

It will also be understood that our invention may be applied to the construction of piles for T-beams or girders, as shown in fig. 3, or to piles for angle-beams, as seen in fig. 4, or to piles of the character illustrated in figs. 5, 6, 7, and 8.

We claim as our invention, and desire to secure by Letters Patent—

A pile or fagot, for wrought-iron beams or girders, &c., composed of one or more bars for the web, and three or more bars for each flange, when the said bars are arranged and permanently secured together by bolts or rivets, as and for the purpose described.

In testimony whereof we have signed our names to this specification in the presence of two subscribing witnesses.

GEORGE WALTERS,
THOMAS SHAFFER.
